ATTORNEY

UNITED STATES PATENT OFFICE.

FRANK COBURN HUBBARD, OF DENNIS, TEXAS.

SAW ATTACHMENT FOR VEHICLES.

Application filed August 5, 1925. Serial No. 48,411.

To all whom it may concern:

Be it known that I, FRANK C. HUBBARD, a citizen of the United States, residing at Dennis, in the county of Parker and State 5 of Texas, have invented new and useful Improvements in Saw Attachments for Vehicles, of which the following is a specification.

This invention relates to improvements 10 in saw attachments for use upon motor vehicles and contemplates the provision of a saw frame adapted to be secured to the vehicle frame and having a saw mounted upon its forward end and receiving its 15 power transmitted by the forward end of the vehicle crank shaft.

Another object of my invention is the provision of the power transmitting apparatus for the saw in the provision of a 20 shank secured to the crank shaft fan pulley and having a socket within its forward end for receiving the saw shaft therein whereby the said crank shaft will move as a unit with the said saw shaft.

With the above and other objects in view, 25 the invention further includes the following novel features and details of construction, to be hereinafter more fully described, illustrated in the accompanying drawings 30 and pointed out in the appended claims.

In the drawings:—

Figure 1 is a front elevation of a motor vehicle showing my present invention applied thereto.

Figure 2 is a fragmentary side elevation 35 showing the manner in which my frame is attached to a vehicle.

Figure 3 is a top plan view of the saw and saw frame, *per se*.

Figure 4 is a sectional view taken through 40 a portion of the vehicle frame and showing the manner in which my invention is attached thereto.

Figure 5 is a fragmentary perspective of 45 the inner end of the saw frame and showing the attaching means thereon.

Figure 6 is a perspective of a fastening element to be secured to the vehicle side bars.

Figure 7 is a sectional view taken on line 50 7—7 of Figure 8.

Figure 8 is a sectional view taken on line 55 8—8 of Figure 7.

Figure 9 is a perspective of a shaft coup-

Referring to the drawings in detail, wherein like characters of reference denote corresponding parts, the reference character 10 indicates a Ford automobile which is shown as having my present invention applied thereto, although I have shown my invention as applied to this particular form of automobile, it is of course understood that I do not limit myself to attaching the same to any one form of automobile but 60 that minor changes in the form and construction thereof may be made in order that the said invention may be applied to all types of motor vehicles.

The saw frame comprises spaced parallel 70 angle bars 11 having correspondingly shaped cross bar 12 arranged between their inner sides and adjacent the forward ends thereof and which has bearingly mounted as at 13 to the upper side thereof a saw 75 shaft 14 carrying a saw 15 upon its forward end and reduced and squared portions 16 and 17 upon the inner end thereof. Arranged upon the upper sides of the angle bars 11 and adjacent the inner ends thereof 80 are angle brackets 18 having their angular portions extending upwardly from the outer sides of the angle bars terminating in substantially V-shaped cutout portions 19 upon the upper ends thereof and which are 85 adapted to receive the inner end portions and under sides of the combined lamp brackets and fender braces 20. These brackets 18 are held rigidly positioned 90 against these combined lamp brackets and fender braces 20 through the instrumentality of substantially L-shaped bolts 21 having their offset portions extending over the brackets 18 and adapted to engage the upper sides of the combined lamp brackets 95 and fender supports 20 whereby the said angle bars 11 will be rigidly secured to the vehicle 10. It is my purpose in so associating this frame to the motor vehicle 10 as to 100 take out all vibrations, shocks and the like so that my saw 15 will run evenly and smoothly and in order to accomplish this result the inner ends of the angle bars 11 include slots 22 within their inner ends and which are adapted to receive therein the offset portions 23 of plates 24 secured at 105 their upper ends to the outer sides of the vehicle side bars as clearly illustrated in Figure 2 of the drawings. It will thus be noted that my frame is rigidly supported 110

upon the vehicle 10 and all such vibrations, knocks and the like will not occur and interfere with the operations of the saw 15 and its shaft 14.

6 In order to provide means upon this vehicle 10 for imparting the necessary force, momentum or power to operate the shaft 14 and saw 15, it is necessary to remove the vehicle hand crank and ratchet therefor 19 from the vehicle, not shown, and associate with the motor vehicle crank shaft 25 within the fan pulley 26, a stub shaft 27 having an enlarged hollow portion 28 upon its inner end for the reception of the fan 15 pulley hub and reduced forward end portion of the crank shaft 25 therein and including diametrically opposed longitudinally extending slotted portions 29 extending inwardly from the inner ends thereof for 29 the reception of a pin 30 extending through the hub portions of the fan pulley 26 and reduced end portion of the crank shaft 25 and which is ordinarily used for engaging the ratchet upon the inner end of the hand 25 crank, not shown. The forward or outer end of the stub shaft 27 includes a squared socketed portion 31 and within which is inserted the inner squared portion 17 provided upon the inner end of the saw shaft 14 whereby the said shaft 14 and saw 15 will be set in motion upon the successive revolutions of the motor vehicle crank shaft 25.

It is further to be noted that owing to 35 the simplicity of construction and arrangement of parts of the stub shaft and the manner of association thereof with the fan pulley 26 and crank shaft 25 that the same may be manufactured in great numbers and sold 40 at a very nominal cost and can be attached and removed with little difficulty. An adjustable thrust collar 32 upon the shaft 14 will eliminate any thrust or end play and hold the squared end portion 17 of the shaft 45 14 within the stub shaft 27 and the enlarged socketed portion 28 upon the pulley 26 and crank shaft 25. A platform 33 being arranged upon the under sides and adjacent the outer ends of the angle bars 11 for supporting timber and other articles to be cut 50 by the saw 15. The thrust-bearing is

clearly illustrated in Figure 3 of the drawings.

The invention is susceptible of various changes in its form, proportions and minor 55 details of construction, and the right is herein reserved to make such changes as properly fall within the scope of the appended claims.

Having described my invention what is 60 claimed is:—

1. A saw attachment for use upon motor vehicles comprising a pair of angle bars having elongated longitudinally disposed slots upon their inner ends including a cross 65 bar secured to the inner sides and adjacent the forward ends thereof, offset plates secured to the outer sides of the vehicle side bars and receiving the slotted portions of the angle bars thereon, angle brackets 70 secured to the upper sides and adjacent the inner ends of the angle bars and engaging the under sides of the vehicle fender brackets, substantially L-shaped bolts secured to the upper sides of the angle bars 75 and engaging the upper sides of the fender brackets, a saw shaft journaled upon the upper side of the cross bar, and a stub shaft arranged within the vehicle fan pulley and having its outer end connected to the saw 80 shaft for imparting a source of momentum thereto.

2. A saw attachment for use upon motor vehicles comprising a pair of angle bars supported upon the motor vehicle chassis, a 85 cross bar secured to the inner side and adjacent the forward ends thereof, offset plates secured to the outer sides of the vehicle side bars for engaging the inner ends of the angle bars, bracket bars arranged upon the angle bars for engagement with the motor vehicle fender brackets, bolts arranged upon the upper side of the angle bars and engaging the corresponding portions of the fender brackets, a saw shaft arranged upon the cross bar, and a stub shaft arranged upon the vehicle and associated with the saw shaft for imparting a source of momentum thereto.

In testimony whereof I affix my signature.

FRANK COBURN HUBBARD.
